SUPERREGENERATIVE MAGNETRON
RECEIVER

Rene A. Braden, Collingswood, N. J., assignor to
Radio Corporation of America, a corporation
of Delaware

Application February 29, 1940, Serial No. 321,550,
which is a division of application Serial No.
187,942, January 31, 1938, now Patent No.
2,211,091, dated August 13, 1940. Divided and
this application January 24, 1941, Serial No.
375,793

6 Claims. (Cl. 250—20)

My invention relates to ultra short wave receivers, and more particularly to a receiver having a superregenerative magnetron detector.

This application is a division of my copending application Serial No. 321,550, filed February 29, 1940, for a Superregenerative magnetron receiver, which is in turn a division of my application Serial No. 187,942, filed January 31, 1938, which issued as United States Patent No. 2,211,091, on August 13, 1940.

The practice of superregeneration as applied to thermionic detectors operating in the usual range of radio signalling frequencies is well known. I have discovered that the conditions causing superregeneration which results in the increased sensitivity of an oscillating detector can be applied to a magnetron. Essentially these conditions are met by a detector which is capable of self-oscillation when suitable values of electrode potentials are applied and in which oscillations are interrupted by periodic variations of the electrode potentials.

It is an object of this invention to provide means for obtaining superregeneration in a magnetron.

My invention will be better understood from the following description when considered in connection with the accompanying drawing. Its scope is indicated by the appended claims. The figure of the drawing is the circuit diagram of a circuit for producing superregenerative action by means of a variable impedance connected across a transmission line in the oscillatory circuit.

Referring to the drawing, ultra short wave signals are received on the antenna 15 and fed by transmission line 151, 153 to the anode electrodes 3 and 5 of the magnetron 167, which also includes a conventional linear cathode 7 energized by a battery 9, or the like. An electro or permanent magnet for producing a strong magnetic field which surrounds and is substantially parallel to the cathode is represented by the pole pieces 2 and 4.

Anode potential for the magnetron is supplied by a battery 31 which is connected to the mid-point or electrical center of the antenna 15, or an equivalent point, through a resistor 19 and a radio frequency choke 17. A voltage corresponding to the modulation frequency component of the received signal is developed across resistor 19. This voltage is impressed on the output device, such as a modulation frequency amplifier and detector 29, through a coupling capacitor 27.

Quenching of the signal frequency oscillations

is obtained by means of a damping tube 169 connected to a voltage loop in a transmission line 151, 153 between an antenna 15 and a magnetron detector 167. This tube may be a magnetron or other thermionic tube. The transmission line is resonant at signal frequency. It is of sufficient length to provide the proper matching between antenna and oscillator and in addition to have available at least one voltage loop. Tube 169 is preferably connected to the transmission line at a voltage loop by very short leads. The anode electrodes 155 and 157 may be incorporated as a section of the transmission line instead of being attached by separate leads. While the tube 169 may be operated as a negatively biased, positive plate triode, I prefer to operate it with a positive grid and a small positive or negative bias on the anodes.

Tube 169 consists of two anode electrodes 155 and 157 which are respectively connected to lines 151 and 153. A cathode 159 is energized by a battery 9. An accelerating grid 161 which is between the cathode and the anodes is connected to one terminal of inductor 165. The remaining terminal is connected through a source of grid potential 171 to one side of the cathode. The anodes are at a high positive potential with respect to ground. A battery 163 is connected between one side of the cathode and the high side of battery 31. The polarity and potential of battery 163 may be adjusted to obtain the desired cathode-anode voltage.

The potential of accelerating grid 161 is varied by the quench frequency oscillations which are impressed on it from an oscillator 25. The effect of this is to vary the shunt impedance of the tube 169 across the transmission line. The short-circuiting effect which is produced in the magnetron 167 interrupts its signal frequency oscillations at the quench frequency, and superregeneration takes place.

While I have shown the damping tube 169 connected across the transmission line at a voltage loop, it would also be effective if coupled to this point by a resonant transmission line of suitable characteristics.

I claim as my invention:

1. In an ultra high frequency receiver consisting of an antenna, a magnetron oscillating at signal frequency, a transmission line connecting said antenna to said magnetron, said line being resonant at said signal frequency and having at least one voltage loop between said antenna and said magnetron, and means for indicating demodulated signals, the method of obtaining

superregenerative detection which comprises varying the shunt impedance of said transmission line at said voltage loop at a quench frequency, thereby interrupting said signal frequency oscillations at the quench frequency.

2. In a superregenerative detector, the combination including an oscillating detector, a standing wave oscillatory circuit connected to said detector, variable impedance means connected across said oscillatory circuit, and means for varying the impedance of said variable impedance means at an inaudible frequency to produce superregenerative detection by interrupting the oscillations of said detector.

3. A device of the character described in claim 2 in which said variable impedance means comprises a vacuum tube having a pair of anodes connected to said oscillatory circuit, a cathode, and a grid for varying the impedance of said variable impedance means.

4. A device of the character described in claim

2 in which said variable impedance means is connected between voltage loops on said standing wave circuit.

5. In a superregenerative detector, the combination including an oscillating magnetron detector, an antenna, a standing wave oscillatory circuit coupling said antenna and said detector, and variable impedance means in shunt with said circuit for interrupting said oscillations at a supersonic rate.

6. In a superregenerative detector, the combination including an oscillating magnetron detector, an antenna, a standing wave oscillatory circuit coupling said antenna to said detector, means including a variable impedance electronic device connected across said line for interrupting the oscillation of said detector at a supersonic rate, and output means for deriving rectified currents from said detector.

RENE A. BRADEN.
